N. Y., a corporation of Delaware

Application February 6, 1945, Serial No. 576,398

19 Claims. (Cl. 177—353)

1

This invention relates generally to communication and posting systems for displaying information or data in regard to a number of different items by means of groups or rows of indicators which are automatically and selectively actuatable or settable in response to incoming signals to display information or current changes in information in regard to the items posted, and is particularly applicable, although not limited, to a system for the transmission, recordation and posting of data on announcement or bulletin boards relating to air traffic control information, in which the signals representing the information thus posted may be transmitted either from a local transmitter or from wire or radio transmitters remotely situated with respect to the receiving, posting and recording apparatus, which remote transmitters may be located at ground stations or within aircraft in flight. The system disclosed herein represents in various respects an improvement over the communication and posting systems disclosed in the Marshall et al. patent, No. 2,246,449, issued June 17, 1941, and in the May et al. Patent No. 2,386,743, issued October 9, 1945, and the Marshall et al. Patent No. 2,391,469, issued December 25, 1945, the disclosures of which, insofar as they are pertinent to the present invention, are incorporated herein by reference.

In systems for recording and posting flight plans and flight progress reports of aircraft and other messages relative to the control of aircraft, hereinafter referred to as air traffic control systems, the information thus posted on the bulletin or announcing board usually relates to numerous flights, and the items posted usually are arranged in groups according to the various "marker" or "Fix" classifications, as explained in the aforesaid Marshall et al. patent, and preferably are arranged within each Fix group in accordance with the expected or estimated time of passage or arrival of the aircraft at the various recording or marker points en route and at the airport. The flight data posted may have to be changed from time to time during the progress of the flights as the result of conditions affecting the progress of aircraft, such as poor visibility, ice, changes in the direction and velocity of the wind, the necessity for blind landings, and other emergency conditions.

The information posted may comprise numerous data, such as the flight designation symbols followed by a section number, if any; information as to the direction of the various flights; the airway traffic controller's estimated

2

time when the aircraft will pass over or land at certain marker points on the flight route; the time the aircraft actually passes over or lands at each marker point; the expected approach time when the pilot may receive instructions to start his approach to a landing field; proposed altitudes at which a clearance has been issued to cross each marker or flight path; the altitude and time at which the aircraft actually crosses the various markers; and the landing sequence number assigned to landings under instrument conditions. In addition to the foregoing, other information may be posted on the flight progress display boards, such for example as an indication that a clearance through a fix or control zone has been issued; an indication of a flight over the airport; an indication of a stop en route, and the expected approach time, or that if a delay is encountered the degree of such delay is unknown; and an indication that an aircraft has been cleared to the airport control tower or range station so that there will be no unnecessary delay in landing.

Local communication facilities comprising known telephone or telegraph wire or radio equipment may be employed to establish communication between the air line company's dispatch offices and the various aircraft, airport control towers, the local communications operator of the airway traffic control, government regulating bureaus, local military operations offices, if any, and other airports.

In prior systems of the character disclosed herein, and particularly air traffic control systems, if an incoming message in regard to a particular flight or other item to be posted contained more than one kind of data for the same display item, for example, altitude and time, it was necessary to repeat the item or flight identification, including the fix, for each of the various kinds of data during the transmission of the message, and to effect the posting of the individual ranges of data relating to the item successively on the record or display board, thereby involving as many posting operations as there were different kinds, or ranges, of data. This causes an undesirable loss in time, both in the transmission and posting of the data, and also is subject to a further objection in that the several indicators for displaying an item posted on the display board are not simultaneously or concurrently reset when a change in data is to be effected, and thus for a period of time certain of the indicators assigned to an item may display current data while others are displaying obsolete data in regard to

the item, the disadvantages of which are apparent.

One of the objects of the present invention is to provide suitable means for effecting multiple "range" posting thereby to enable the concurrent or simultaneous posting of a plurality of different kinds, or ranges, of data pertaining to a particular item of the display board. In the instant disclosure, the concurrent or simultaneous posting of all ranges pertaining to a specific item prevents likelihood of confusion, and results in a faster and more efficient system since the posting time is greatly reduced. This saving in time is particularly important when a message is received as a result of an initial automatic retransmission from another center. In such cases, all available data pertaining to a specific flight or other item are embodied in a single message and, therefore, the posting of the display board at the receiving center usually comprises a plurality of data ranges.

In air traffic control procedure it is at times required that certain information displayed on a flight progress board at a traffic control center be retransmitted to another center or to an auxiliary board such, for example, as an airport control tower or range station. Such retransmissions are usually not made at the time the information is originally posted at the retransmitting point, but instead are initiated at some later period, depending upon the progress of the flight in question. For example, assume that a flight plan is posted on a flight progress board at the Washington control center for an aircraft flying the New York to Washington airway. The Washington airways traffic control center board would, in this instance, display the flight information at fix or check points in the Washington control area, viz.—Philadelphia, Baltimore and Washington. Assume further that an auxiliary display board is located at the Washington Airport tower. This latter board would display information relative to the Washington fix only, since the tower personnel are concerned only with traffic in the immediate vicinity of the Washington Airport.

It will be apparent that, while the airways traffic control board must display the Washington fix posting prior to the entrance of the flight into the Washington airways control area (in the neighborhood of Philadelphia on a southbound flight), the Washington tower board does not require this information until a much later time when the aircraft is about to enter the immediate control zone of the Washington tower. At this later time, the tower board must duplicate the existing information displayed for the specific flight on the Washington fix section of the main airways traffic control board. The retransmission to the tower board at this time is not necessarily a duplication of all the previous messages which caused a display of information on the Washington fix section of the main board, but rather is a retransmission of the current display. The distinction is that the tower personnel are not interested in prior information which may have been revised by changing flight conditions. Following the original retransmission, however, any change in the information posted on the main board should automatically be relayed to the tower board. It is to be understood that retransmission is not limited to a tower board, but may be made to a center in another control area, military or naval control centers, and the like.

Another object of the invention is the provision of means operative upon the occurrence of a particular event or condition for automatically retransmitting selected data currently posted on a record or display board to another center or to an auxiliary board for recording or posting such information on the other board, thereby to duplicate at certain times the desired data, and thereafter to cause changes effected in said data posted on the record or display board also to be effected automatically at the other center or auxiliary board.

The information displayed on a given "fix" posting of a flight progress board is usually retained until the aircraft has reported over the next fix, or check point, on its course along the airway. Previous air traffic control systems have provided for a wipe-out of the obsolete display by means of a manual keyset operation.

Another object of the present invention is to provide means for a wholly automatic wipe-out at the previous fix posting, upon the occurrence of a particular event or condition, for example, as when an "over" report is received i. e., the time at which an aircraft reaches or passes a certain fix. Automatic reference may be made to the direction of flight, obtained from a "bound" digit of the existing display, and the fix section at which the "over" report is received, to determine the previous fix section at which the automatic wipe-out of the flight posting in question must be made. This wholly automatic feature eliminates the manual operations heretofore necessary and results in increased speed and efficiency.

An additional object of the present invention is to provide suitable automatic alarm means to attract the immediate attention of airways traffic control personnel in the event that certain special conditions occur or obtain, for example, as when an "over" report is received from an unscheduled aircraft at any fix within the control area.

These and various other objects, advantages and improvements of the present invention will be apparent from the following detailed description of one illustrative embodiment of the invention taken in connection with the accompanying drawings, in which:

Fig. 1 is a view in diagrammatic form of certain transmitting and receiving apparatus including a seeker mechanism and message counting storage indicators suitable for use in the system of the invention;

Fig. 2 is a diagrammatic representation of the announcing or display board containing storage display indicators, together with the tens digit translating relays and certain identification or flight locator relays;

Fig. 3 shows groups of translating relays with associated control relays and a retransmission distributor with associated control and switching relays, the figure also illustrating diagrammatically a retransmission tape perforator, tape transmitter and transmitting distributor;

Fig. 4 illustrates a receiving distributor controlled by signals received from the transmitting apparatus of Fig. 1, together with distributor control relays and the tens and unit flight identification decoding relay groups;

Fig. 5 shows fix, range and data decoding relay groups, range transfer, fix and direction relays and flight identification storage indicators and tap switches employed in the flight locator circuit;

Fig. 6 shows a pulse distributor, data storage

and data restoration groups and associated control relays;

Fig. 7 illustrates an arrangement of the display board on which the flight control information is posted;

Fig. 8 shows various permutation signal codes suitable for use with the system; and

Fig. 9 is a diagram showing the arrangement of the various sheets of drawing illustrating the system.

For the sake of simplicity, the detailed description of a system embodying the invention is limited to the transmission, reception and storing or posting of but a few ranges, or kinds, of data, for example, "over" (actual time), "bound" (direction), and "control" (specific operational information or instructions), but it is to be understood that in actual practice additional data ranges, such as estimated time, altitude and others previously mentioned herein, also would be transmitted, received and stored or posted generally in the manner of the ranges specifically referred to in the detailed description. Likewise, for simplicity, the number of denominational rows of digits for a particular range has been limited to one or two; in practice a greater number would be employed for certain ranges as well as for the flight identification groups.

Seeker and message counting circuits

In the system of the aforesaid Marshall et al. Patent 2,246,449, a condition may arise wherein, assuming the operator at the remote sending point transmits another message over the same line before the end-of-message character in the first message has passed through the common retransmitting and posting system, the seeker connection is held by the auto-control contact of the associated tape transmitter, thus allowing the remote operator to post two or more independent messages in succession. In the present system the number of complete messages transmitted by a remote point preferably is counted by suitable means, such as a storage indicator unit, as the end-of-message character for each message is transmitted, and a second associated means, such as a storage indicator unit, is used to count the end-of-message character as it passes through the common retransmitting and posting equipment. Any disagreement in the settings of the associated indicator units is an indication to the seeker that an incoming message from the associated line is awaiting connection to the common posting system. With this feature, it is impossible for a partial message from a remote sending station to cause a tie-up of the common posting system, since no indication is given to the seeker at any time until a complete message, including the end-of-message character, has been received. Also, since a count of incoming messages up to ten in number is kept on the associated indicator unit, no lost postings will result due to a plurality of messages being received over a particular line at the time the common posting system is connected by the seeker to a different incoming line.

Assume, for example, that the flight progress board depicted in Fig. 7, is located at the Washington Airport, and messages are being transmitted simultaneously from telegraph transmitters, for example, keyboard transmitting teleprinters 1 and 2, Fig. 1, over lines L and L₂. Teleprinter 1 may, for example be located at the New York control center and is assumed to be in the process of transmitting two successive,

independent messages for posting on the Washington flight progress board, whereas teleprinter 2, which may be located in an aircraft over the Baltimore fix is assumed to be in the process of transmitting an over report for display on the Washington board. A local transmitter 3, which may be a teleprinter, is provided to enable the personnel at the control center to post, reset or wipe-out the display at will.

- 10 The preliminary operations resulting from the transmission of the first message from the New York teleprinter will now be described. Assume the message concerns flight 35 and contains Bound and Control data for this flight at the 15 Philadelphia fix section of the Washington board. The New York operator actuates the keys of his teleprinter in the following order: 3532431L. The first two characters transmitted 35, represent the flight identification number; the third character 3, represents fix 3, or Philadelphia; the fourth character represents the range Bound; the fifth character 4, represents the direction data digit South; the sixth character 3, represents the range Control; the seventh character 1, represents the "control" data digit; and the eighth, or final, character L represents the end-of-message signal. It should be explained here that the direction digits usually are assigned to correspond to points of the compass so that, starting with northeast as the digit 1 and progressing clockwise, the digit 4 represent south direction and the digit 8 would represent north direction. For purposes of simplification, only the north and south direction circuits have been shown on 35 the drawings. Likewise, the "control" data digit represents an arbitrary assignment to indicate the specific instruction issued to the pilot of the aircraft in question. For example, the digit 1, in the "control" range might indicate 40 "cleared to the New York boundary." This would be an indication to the Washington personnel that the New York control center had cleared flight 35 to the point where Washington assumes control. Other digits are assigned similarly, the digit 2, for example, could indicate "instructed to hold at this fix," etc.

The keyboard printer referred to above may be one of any of the well known types suitable for the purpose such as, for example, what is known 50 in the telegraph art as a 2B printer that records the signals on a tape in response to start-stop or simplex type signals, such signals being composed of marking and spacing line conditions comprising a start impulse followed by groups of 55 permutations of five intelligence impulses in various combinations representing the characters to be transmitted or received, and each group being terminated by a rest impulse which is of opposite line condition to that of the start impulse. The 60 actuation of any of the keys of the associated keyboard causes the transmission of signals representing the character assigned to each key.

The operation of the flight identification key 3 causes a start signal to be applied to the line 65 L, thereby starting operation of receiving distributor 4. This signal is followed by a five unit code permutation signal for the first digit (3) of the flight identification number, this signal having the code unit 1 thereof marking and the code units 2, 3, 4 and 5 spacing in character, Fig. 8, followed by a rest, or stop, signal. The operation of distributor 4 causes the marking and spacing code units 1, 2, 3, 4 and 5 of the intelligence signal to be transmitted to the tape 70 reperforator 5 over the conductors 6, 7, 8, 9, and

10 respectively. Following this, an impulse is transmitted in known manner by the distributor over conductor 11 to operate the punch magnet and cause the reperforator to perforate the tape 12 issuing therefrom in accordance with the signals received and step the tape ahead into position for the next succeeding perforating operation corresponding to the second digit of the flight identification number. Since the permutation signal for the digit 3 has the code unit 1 only marking in character, conductor 6 is energized and conductors 7, 8, 9 and 10 are deenergized, thereby causing a single perforation corresponding to the code unit 1 to be made in the tape 12 at this time.

Conductors 6, 7, 8, 9 and 10 are connected by way of conductors 1, 2, 3, 4 and 5 of cable 13 to the windings of the end-of-message reading relays EM-1, EM-2, EM-3 and EM-4 respectively. Energization of conductor 6 causes relay EM-1 to operate by way of conductor 1 of cable 13. Relay EM-1 locks through its make contact and armature 14 to battery on conductor 15 supplied by the break contacts of the sixth pulse relay 16 of the distributor 4. The operation of relay EM-1 is without effect at this time, relay EM-1 releasing upon the subsequent operation of the sixth pulse relay of the distributor. In a similar manner, the signals corresponding to the digits 5, 3, 2, 4, 3 and 1 are received and stored in the perforated tape 12 and also cause the operation of the end-of-message relays EM-1 to EM-4 in code combination corresponding to each of the digits stored in the tape.

Immediately following the signal for the digit 1 is the end-of-message signal which, in the assumed example, is the signal representing the character L having code units 1, 2 and 4 spacing and units 3 and 5 marking. This signal causes relays EM-2 and EM-4 to operate and lock to battery on conductor 15, and relays EM-1 and EM-3 to remain unoperated. Battery at armature 17 and make contact of relay EM-4 is extended to armature 18 and break contact of relay EM-3, armature 19 and make contact of relay EM-2, armature 20 and break contact of relay EM-1 and thence by way of conductor 21 to the winding of storage indicator unit MR-1 and thence to ground. The storage indicator may be of any suitable type, for example, as disclosed in Haselton et al. Patent No. 2,155,825, issued April 25, 1939. Upon the release of relays EM-2 and EM-4 when the sixth pulse relay 16 operates, storage indicator unit MR-1 is stepped or advanced one position as its coil is again deenergized. Assuming no unposted messages for line L preceded the transmission just described, indicator unit MR-1 will now be one position in advance of the setting on the storage indicator unit MP-1. Like terminals of the bank contacts of units MR-1 and MP-1 are connected together, so that whenever the two units are in agreement as to setting, a circuit is established from battery 22 over rotary wiper 23 of unit MR-1, thence by way of contact 24 of unit MR-1, contact 25 of MP-1, rotary wiper 26 of MP-1, conductor 1 of cable 27 to the winding of relay S1 and thence to ground. It will thus be apparent that, with no completed message awaiting posting, relay S1 is in its operated condition due to agreement of the associated indicator units MR-1 and MP-1. The message transmitted from New York, as described above, has destroyed this agreement, since unit MR-1 was advanced one step as the

end-of-message character was recorded on the EM relays. Relay S1 is therefore now in its unoperated condition.

Returning to line L2, which it will be remembered is in the process of receiving a message from an aircraft over Baltimore, let us assume that the aircraft operator completes his transmission slightly in advance of the transmission of the end-of-message signal over line L from New York, as noted above. Reception of the end-of-message character over line L2 has caused indicator unit MR-2 to be advanced one position in a manner identical to that described above for unit MR-1. Disagreement between units MR-2 and MP-2 has caused the release of relay S2. As relay S2 released, ground by way of its break contacts 28 was applied to the armature and associated make springs 29 and 30 of relays S1 and S3 respectively, and thence over conductors 1 and 3, cable 31 to bank contacts 33 and 36 of rotary switch SKR. Rotary switch SKR is stepped through a circuit from ground on bank contact 33 of bank X, wiper arm 34, self-interrupting springs 35, and coil of switch SKR to battery. Bank position 32 however, is ungrounded at this time, and the self-stepping circuit of switch SKR is interrupted at this point. With switch SKR positioned so that its associated wipers are resting on the contacts 32, a circuit is established over bank Y to operate connect relay TC-1. The path may be traced from ground on wiper 37 of bank Y, through bank contact 32, thence by way of conductor 2, cable 38, through armature and break contacts 39 of unoperated relay S2, over conductor 2 of cable 40 to the winding of relay TC-1, to battery 41.

Returning to the point where relay S1 has released due to the reception of the end-of-message signal over line L, it will be noted that switch SKR remains positioned to bank contact 32 under control of relay S2, and no further action of switch SKR can occur until relay S2 is reoperated. However, there has been recorded the reception of one complete message over line L which is awaiting connection to the common posting equipment. If it be assumed that the second message from New York over line L is also completed before the posting operation of the message received on line L2 is completed, unit MR-1 will have been advanced an additional step by the reception of the second end-of-message signal, and now will be two positions in advance of associated unit MP-1. Thus, it will be apparent, a count of unposted messages is continually maintained by the relative positions of associated seeker indicator units.

As the message from line L2 is posted on the display board, unit MP-2 is advanced one step over a circuit to be described later. Advancement of unit MP-2 again establishes agreement between settings of units MR-2 and MP-2 and relay S2 is reoperated over a circuit from battery 42 on wiper 43 of unit MR-2, through bank contact 44 on MR-2, bank contact 45 of MP-2, wiper 46 of MP-2, conductor 2 of cable 27, to the winding of relay S2, to ground. As relay S2 reoperates, the operate circuit from relay TC-1 is opened at break contacts 39 of relay S2. The stepping circuit for rotary switch SKR is re-established at this time over a circuit from ground at break contacts 29 of relay S1, make contacts 28 of relay S2, conductor 2 of cable 31, bank contact 32 and wiper of switch SKR, through self-interrupting contacts and coil of switch SKR

to battery. Switch SKR steps on self-interrupted pulses until it reaches an open circuit on bank contact 36. At this point, a circuit is established to operate relay TC which is similar to that described above for operation of relay TC-1.

Multiple range posting

A detailed description of multiple range posting will now be given. Returning to the previous example of a message received over line L from New York containing a "bound" and "control" range posting for the Philadelphia fix section of the Washington flight progress board, there have previously been described the operations up to the point where connect relay TC, Fig. 1, has been operated under control of the seeker rotary switch SKR, indicator units MR-1 and MP-1, and associated relays.

Operation of distributor DR-1.—Relay TC when operated, establishes a circuit to operate the clutch magnet SM-1 of distributor DR-1, Fig. 4. This path may be traced from battery 600 on break contacts 601 of relay RL-3, Fig. 6, over conductor 4, cable 400, conductor 100, Fig. 1, through make contacts 47 of relay TC, over conductor 7 of cable 101, through break contacts 401 of relay ST, Fig. 4, to the winding of start magnet SM-1, to ground. Energization of the coil of SM-1 attracts latch 402, thereby setting the distributor DR-1 into operation. The engagement of brush B1 of the distributor DR-1 with segment 2 of ring R1 closes a circuit from tongue 1 of the tape transmitter TTR-1, contacts 48 of relay TC, conductor 1 of cable 101, segment 1 of ring R2 of distributor DR-1, brush B1, segment 2 of ring R1, conductor 1 of cable 403, break contacts 404 of relay DC, conductor 1 of cable 405, winding of relay 11-1 to ground. The tongue 1 of tape transmitter TTR-1 is in the closed position since the first digit of the flight identification number is 3, and therefore will apply battery 49 to the circuit above described causing operation of relay 11-1. Relay 11-1 locks over its make contacts 496, conductor 6 of cable 400, through break contacts 602 of relay RL-3, Fig. 6, to battery 603.

In a like manner, segment 2 of rings R3, R5, R7 and R9 and associated brushes B2, B3, B4 and B5 of distributor DR-1, Fig. 1, closes circuits from tongues 2, 3, 4 and 5 of tape transmitter TTR-1 to relays 11-2, 11-3, 11-4 and 11-5, respectively. However, none of these relays are operated since the first character perforation in the tape prevents all tongues of the tape transmitter TTR-1 except tongue 1 from engagement with their associated contacts.

As the brushes of distributor DR-1 are disengaged from segment 2 of rings R1, R3, R5, R7 and R9, the circuits from the tongues of tape transmitter TTR-1 to the first digit identification storage and decoding relays 11T-1 to 11T-5, are interrupted. When brush B6 engages segment 2 of ring R11 of the distributor DR-1, ground from break contacts 407 of relay DC over conductor 408 and segment 2 of ring R12 is applied by way of brush B6, segment 2 of ring R11, conductor 6 of cable 101, contact 50 of relay TC to the tape step magnet TS of tape transmitter TTR-1, to battery, thereby causing the tape step magnet to operate and step the tape to the position where the second character in the message is over the tape pins.

As the brushes of the distributor DR-1 move into engagement with segments 4 of rings R1, R3, R5, R7 and R9, the tongues of tape transmitter

TTR-1 are connected through conductors 6, 7, 8, 9 and 10 of cable 403, break contacts 409, 410, 411, 412 and 413 of relay DC and conductors 6, 7, 8, 9 and 10, of cable 405 to the windings of the second digit identification storage relays 21-1 to 21-5, Fig. 4. This group of relays is identical with the first digit relays 11-1 to 11-5 and is therefore indicated in diagrammatic form by the rectangles 414 and 427. The identification digit, 10, has the code unit 5 marking and units 1, 2, 3 and 4 spacing and therefore relay 21-5 will be the only relay of the second digit identification group to operate. The second digit identification storage relays lock over the same circuit as described above for the first digit group.

As brush B6 of the distributor DR-1 engages segment 4 of ring R11, ground is again applied over the circuit previously described to the step magnet TS of tape transmitter TTR-1, thereby advancing the tape 12 to the position where the next character perforations corresponding to Fix 3 (Philadelphia) are over the feeler pins of the tape transmitter.

As the respective brushes contact segment 6 of rings R1, R3, R5, R7 and R9, battery is applied to conductor 11 of cable 403, through break springs 415 of relay DC, through conductor 11 of cable 405, to the winding of fix selection relay F1, Fig. 5, to ground, causing operation of relay F1 which locks over its make contacts 500 and conductor 501, conductor 5 of cable 416, to break contacts 417 of relay RL-1, Fig. 4, to battery. With relay F1 operated, ground is extended through the pyramidal contacts of relays F1 to F5 to operate the "Philadelphia" fix relay, FX-3. The circuit may be traced from ground on make contacts 502 of relay F1, through break contacts 503 of relay F2, break contacts 504 of relay F3, break contacts 505 of relay F4, break contacts 506 of relay F5, over conductor 3 of cable 507, to the winding of relay FX-3, to battery. Relay FX-3 locks over a path through its make contacts 508, conductor 2 of cable 509, conductor 2 of cable 400, to break contacts 604 of relay RL-3, Fig. 6, to ground. As brush B6 contacts segment 6 of ring R11, the tape transmitter receives another stepping pulse as previously described and the tape character over the feeler pins of tape transmitter TTR-1 is now the range digit.

Engagement of segment 8 of the distributor rings by the brushes B1 to B5 applies battery over conductors 16, 17 and 20 of cable 405 to operate range storage and decoding relays R1, R2 and R5, Fig. 5, which lock over the same circuit as described for the fix selection relays. The operation of relays R1, R2 and R5 closes a circuit through the pyramidal contacts of relays R1 to R5 to operate "bound" range transfer relay B. The circuit may be traced from ground on make contacts 510 of relay R1, through make contacts 511 of relay R2, break contacts 512 of relay R3, break contacts 513 of relay R4, make contacts 514 of relay R5, over conductor 2 of cable 515 to the coil of relay B, to battery. The operation of range transfer relay B conditions the stepping circuit from distributor DR-1 to the tape transmitter step magnet for reception of a single data digit and also transfers the pyramidal output of the first data translating relay group to the "bound" data storage relay group BS-1 to BS-4, Fig. 6. Relay B operated closes a circuit from battery 539, through its make contacts 516 and conductor 18 of cable 517, to the winding of the B range restoration relay BR, to ground. Relay BR operates 75 and locks over its make contacts 605 and con-

11

ductor 606 to break contacts 607 of relay AG, to battery.

As brush B6 contacts segment 8 of ring R11, the tape is again advanced and positioned so that the data character 4 is over the tape transmitter feeler pins. When brush B6 contacts segment 9 of ring R11, a circuit is established from ground on break contacts 418 of relay ST, through conductor 419, through segment 4 of ring R12 and brush B6 to segment 9 of ring R11, over conductor 420, to the winding of relay DC, to battery, causing relay DC to operate and lock through its make contacts 421 to break contacts 423 of relay ST, to ground.

Engagement of segment 10 of the distributor rings by the brushes B1 to B5 applies battery over conductors 22 and 24 of cable 405 to operate data decoding relays DT-2 and DT-4 which lock over the same circuit as described for the fix selection relays. The DT and DU relay groups are identical to section 424 of the II relay group and have therefore, for simplicity, been indicated in diagrammatic form as box 517 and box 556. Circuits through the DT relay contacts may be traced by reference to corresponding numbers on the pyramidal contacts of the II relay group. Thus, operation of relays DT-2 and DT-4 establishes a circuit which may be traced from battery 518 through break contacts of relay DT-1 (corresponding to 426 of II-1), make contacts (428) of relay DT-2, break contacts (429) of relay DT-3, make contacts (430) of relay DT-4, break contacts (431) of relay DT-5, conductor 3 to make contacts 520 of range connect relay B, conductor 11 of cable 517, to the winding of relay BS-3, Fig. 6, to ground. Relay BS-3 locks over its make contacts 608, conductor 609 to battery on break contacts 610 of relay RL-3. The foregoing operation which resulted in the energization of bound data storage relay BS-3 has, in effect, translated the character 4 from the teleprinter code to a pulsing code on the pyramidal contacts of relays DT-1 to DT-5, and has stored the resultant on storage relay BS-3. It will be understood that the translation to pulsing code made on the contacts of the DT relays is to effect subsequent pulsing, by means of a number of stepping pulses, of the display indicator units to settings corresponding to the data digits transmitted from the remote teleprinter. In addition to the operation of relay BS-3, relay BR has also been operated and subsequently will be used to effect the restoration to blank of any existing display on the selected "bound" data display indicator.

Following the above described operation, brush B5 of distributor DR-1, Fig. 4, contacts segment 10 of ring R11 and the tape is advanced one step as described previously. Engagement of segment 12 of the distributor rings by the brushes B1 to B5 applies battery over conductor 26 of cable 405 to operate relay DU-1, Fig. 5, which locks over the same circuit as described for the DT relays. Operation of relay DU-1 has no effect at this time, since the circuit from the pyramidal contacts is open at the V relay contacts. Distributor brush B6 next contacts segment 12 of ring R12 but no tape transmitter stepping action results since segment 5 of ring R12 has had its ground connection removed by the operation of range connect relay B. The circuit may be traced from segment 5 of ring R12, over conductor 3 of cable 416, to open break contacts 521 of operated relay B. As brush B6 contacts segment 14 of ring R11, a circuit is established from ground on segment 6

12

of ring R12, through brush B6 and segment 14 of ring R11, over conductor 433, to the winding of relay RL-1, to battery. As relay RL-1 operates, the locking circuit to the fix, range, and data decoding relays is opened at break contacts 417 of relay RL-1 and any of these relays which have been operated are released. Release of the R1, R2 and R5 relays causes release of relay B which was being held operated through pyramidal contacts on these relays.

Since clutch SM-1 is still energized, the brush arm of distributor DR-1 makes a second revolution at this time. As brushes B4 to B6 contact segments 2, 4 and 6 of rings R1 to R11, no circuits are established since conductors 1 to 15 of cable 403 are opened at the break contacts of operated relay DC, and the ground connection to segment 2 of ring R12 of the tape-stepping circuit is opened at break contact 407 of operated relay DC. As brushes B1 to B5 contact segment 8 of rings R1 to R9, the R-1 relay of the range decoding group is operated in accordance with the code for character 3 which is still over the tape transmitter feeler pins. Relay R-1 locks over the circuit previously described and closes a circuit to operate range connect relay C, Fig. 5, over a circuit from ground on make contacts 510 of relay R1, through break contacts 522 of relay R2, break contacts 523 of relay R3, break contacts 524 of relay R4, break contacts 525 of relay R5, conductor 3 of cable 515, to the winding of relay C, to battery. Relay C operated, transfers the output of the DT relay decoding pyramid to the CS relay group in Fig. 6. Storage relay CS-1 is operated as a result of the final data digit perforated in the tape in a manner similar to that described for the B data character. Relay C operated also causes operation of C data restoration relay CR over a circuit similar to that described for the operation of BR relay.

At this point, the data for the two ranges in the assumed transmission have been decoded and stored on the proper storage relay groups of Fig. 6 in readiness for the actual posting operation. Note that, if the data for the range in question consists of more than one digit, as for example, V or "over" range, the tape transmitter stepping circuit is not opened as the brush B6 contacts segment 12 of ring R11, since the ground connection to segment 4 of ring R12 is uninterrupted by operation of V range connect relay.

Returning to the operations resulting from the example under consideration, as the brush arm of distributor DR-1 makes its third revolution, the final character in the tape is over the tape transmitter feeler pins, viz., the L or end-of-message signal. In the manner previously described, relays R-3 and R-5 will be operated as brushes B1 to B5 of distributor DR-1 contact segment 8 of the associated rings. Relays R-3 and R-5 operated, establish a circuit for operating the end-of-message relay EM, Fig. 2. The path may be traced from ground on break contacts 526 of relay R-1, through break contacts 527 of relay R-2, make contacts 528 of relay R-3, break contacts 529 of relay R-4, make contacts 530 of relay R-5, over conductor 3 of cable 509, to the winding of relay EM to battery. Relay EM locks over its make contacts 200 through conductor 2 of cable 400, to break contacts 604 on relay RL-3, to ground.

Relay EM operated, establishes a circuit from battery on its make contacts 201, over conductor 1 of cable 416, to the winding of relay ST, Fig. 4, to ground. Relay ST operates and locks over its

make contacts 435 and conductor 7 of cable 101 through make contacts 47 of relay TC, over conductor 100, to conductor 4 of cable 400, to break contacts 601 of relay RL-3, Fig. 6, to battery.

The break combination of contacts 401 of relay ST opens the circuit to the winding of start magnet SM-1 of distributor DR-1 so that the latch 402 will engage the brush arm and stop its movement at the completion of the third revolution. Break contacts 432 of relay ST open the locking circuit to relay DC which releases in readiness for the reception of the next incoming message. As relay EM operated, a circuit was completed from battery on make contacts 202 of relay EM, over conductor 1 of cable 509 through make contacts 531 of operated relay FX-3, to conductor 532, which is multiplied to number 3 contacts of a series of tap switches designated FS-1 to FS-10. These tap switches are associated with corresponding rows of display information on the flight progress board and are manually settable to one of three positions corresponding to the three indicated fix displays. As indicated on Fig. 5, switches FS-1 and FS-2, corresponding to indicator rows 1 and 2 of the display board, are turned to position 1 corresponding to Fix 1, or Washington. The tap switch for row 10 is turned to position 3 corresponding to Fix 3, or Philadelphia. As relay EM operated, another circuit was established from battery on make contacts 203 of relay EM, over conductor 204, through break contacts 205 of relay VS, through break contacts 206 of relay AGR, over conductor 207 to bank contact 208 of rotary switch RS. Bank contact 208 is the homing or idle position of the rotary switch, and therefore at this time, wiper arm 209 of rotary switch RS will be positioned to this contact. The battery connection to bank contact 208 will, therefore, be extended by means of the wiper arm 209, through self-interrupting springs 210 and the winding of switch RS, to ground. Switch RS proceeds to step from its homing position under control of the self-interrupting contact springs. As wiper arm 209 contacts bank positions 2 to 10, a battery connection is made over conductor 211, through break contacts 212 of relay AGR, break contacts 213 of relay VS, to battery 222. It is thus evident that, with relay EM operated, switch RS will step on self-interrupted pulses until either relay AGR or relay VS operates and opens the stepping circuit at break contacts 212 on relay AGR, or 213 on relay VS.

The flight locator circuits under consideration are designed so that a search is made for agreement of flight identification digits as between existing displays on the associated fix section and the new identification information as stored on the pyramids 425 and 427 of the first and second group of storage and decoding relays, II and 21, Fig. 4. In order to effect this comparison, all flight identification digits displayed on the flight progress board are duplicated on associated storage indicator units of suitable type, such as disclosed in the aforesaid Patent 2,155,825. These storage indicator units are shown on Fig. 5 as ITS-1 and IUS-1 to ITS-10 and IUS-10, units ITS-1 and IUS-1 being associated with the tens and units digits of identification displayed on the number 1 row of the flight progress board. The search for agreement is initiated at the lowest numbered row assigned to the fix section in question and progresses upward until identification agreement is found or a row as-

signed to the fix section is reached in which the tens digit of identification storage is blank. If agreement is found, relay AGR, Fig. 2, is operated; if a vacant space is reached, relay VS is operated.

Returning to the present example, it will be noted on Fig. 7 that the two rows of the display board assigned to Fix 3, or Philadelphia, are in use and that flight 35 is posted in row number 10. The manually settable tap switches for rows 9 and 10, or switches FS-9 and FS-10, will be positioned to contact 3, corresponding to the Fix 3, or Philadelphia, section of the display board. It will be recalled that we have previously traced a battery connection as far as number 3 contacts of the fix tap switches. Assuming that rotary switch RS has stepped to the number 10 bank contact position, a circuit can be traced from battery 229 to the number 3 contact of tap switch FS-10, through wiper arm 533 of FS-10, over conductor 10, cable 534, bank 214, contact 10 of rotary switch RS, Fig. 2, wiper 215 of the switch, wiper 216 and contact 10 of bank 217 on switch RS, conductor 10 of cable 218, wiper arm 535 of storage indicator unit ITS-10, bank contact 3 of unit ITS-10, conductor 3 cable 536, break contacts 436 of relay II-5, break contacts 437 of relay II-4, break contacts 438 of relay II-3, break contacts 439 of relay II-2, make contacts 440 of operated relay II-1, conductor 4 of cable 416, wiper 219 and contact 10 of bank 220 of switch RS, over conductor 10 of cable 221 to wiper 537 and bank contact 5 of storage indicator unit IUS-10, conductor 5 of cable 538 to the numerical pyramid 427 of the second digit identification storage and decoding relays 21 (which are storing the digit 5 and therefore have established a path from the apex of the pyramidal contacts to conductor 5 of cable 538 in a similar manner to that described above for conductor 3 of the IT group), to conductor 3 of cable 400, to the winding of relay AGR, to ground. It will be noted that the series circuit just described, which causes relay AGR to operate, is dependent on an exact agreement of both digits of identification as stored on indicators ITS-10, IUS-10 and the storage of the incoming message identification on relay groups II and 21. A search for this agreement was instituted on the first row of information under the Philadelphia fix section, as the rotary switch RS stepped over bank contacts 9, but since the identification displayed on row 9 did not agree with the identification digits transmitted in the incoming message, no complete circuit was established.

As noted before, operation of relay AGR, Fig. 2, interrupts the stepping circuit for rotary switch RS, which is therefore positioned at bank contact number 10. Relay AGR operated, establishes a circuit from battery 222, through make contacts 223 of relay AGR, over conductor 224 to the wiper 225 and contact 10 of bank 226 of switch RS, over conductor 10 of cable 227 to the winding of gang relay GA-10, to ground. Relay GA-10 is therefore operated and connects, by means of its make contacts, the pulsing multiple 619 to the display indicators in row 10 of the flight progress board, Fig. 2, and through cable 257 to the storage indicator units ITS-10 and IUS-10 of Fig. 5. At this point, all preliminary storage and row selection operations have been completed, and the actual pulsing operation of the indicators in accordance with the transmitted information can be initiated.

Operation of distributor DR-2

Relay AGR operated, establishes a circuit from battery 222 through make contacts 228 of relay AGR, over conductor 1 of cable 229, through break contacts 611 of relay PR, Fig. 6, over conductor 4 of cable 229, to the winding of start magnet SM-2 associated with distributor DR-2, to ground. Operation of start magnet SM-2 disengages the latch 612 from the brush arm, thereby setting distributor DR-2 in operation. As brush B1 of distributor DR-2 passes even numbered segments 2 to 20 of ring R1, conductor 614 to the winding of relay P1, to battery. The ten pulses to relay P1 at this time serve to restore to the blank position any previous display which may appear on the indicators of the selected ranges, B and C, of the selected row. The circuit may be traced from ground 613 on ring R2, through brush B1 and segment 2 of ring R1, conductor 614 to the winding of relay P1, to battery. The ten pulses to relay P1 at this time serve to restore to the blank position any previous display which may appear on the indicators of the selected ranges, B and C, of the selected row. The circuit may be traced from battery 615 through make contacts 616 of relay BR, conductor 2 of cable 617, make contacts 618 of relay P1, conductor 7 of cable 619, make contacts 230 of relay GA-10, Fig. 2, winding of display storage indicator B10, break contacts (not shown) of display storage indicator B10, (like the break contacts 231 of storage indicator IT-1 in row one), to ground. The display storage indicators shown in row ten are identical to the unit designated IT-1, and therefore all except this unit are shown in diagrammatic form. These units, which preferably are like the unit disclosed in Haseltine et al. Patent 2,302,769, are unresponsive to restoration pulses when in the blank position due to the interruption of their pulsing circuits by the switching contacts 231 and 232 which are disengaged from each other when the indicators are at their blank settings. The indicator unit in B range of row 10 of the display board will therefore utilize only such pulses of the ten in number originated by relay P1 necessary to restore it to the blank position, at which point the pulsing circuit is automatically opened. If the unit is already in the blank position, the restoration pulses are not effective. Indicator C10 in row 10 is connected to restoration pulses over a circuit similar to that described for unit B10 under control of operated relay CR.

When the brush B1 contacts segment 22 of ring R1 of distributor DR-2, a circuit is closed from grounded ring R2 through brush B1 and segment 22 of ring R1, over conductor 620, to the winding of relay AG, to battery. Relay AG operates and locks over a circuit through its make contacts 621 and conductor 622 to break contacts 623 of relay RL-2, to ground. Relay AG operated, opens the locking circuit for relays BR and CR at its break contacts 607. Relays BR and CR release and open the battery circuits to contacts of the P1 relay which were used in the restoration pulsing operation previously described. Relay AG operated, at its make contacts 624 applies ground over conductor 10 of cable 619 through contacts 234 of relay GA-10 to all contacts 233 of the indicators in row 10 of the display board. This latter circuit replaces the ground connection which is opened by contacts 231 and 232 of the indicator units when they are in the blank position and thus allows any units which may now receive pulses to step from the blank position. The manner in which indicator units B10 and C10 are actuated from their blank settings to display the digits 4 and 1 respectively will now be described.

As the distributor brush B1 passes over the group of segments 24 to 42 of ring R1, a single impulse may be generated from relay P1, two impulses from relay P2, four impulses from relay P4, and seven impulses from relay P7. If an indicator is to be set to display the digit 1, the relay P1 only is employed, if the digit 2 is to be displayed relay P2 only is employed, relays P1 and P2 being employed to display the digit 3. The digit 4 is selected for display on an indicator by the relay P4, the digit 5 by the relays P1 and P4, the digit 6 by relays P2 and P4. When the digit 7 is to be displayed, relay P7 alone is employed. The digit 8 is obtained from relays P1 and P7, the digit 9 from relays P2 and P7 and the digit 0 from relays P1, P2 and P7. The setting of the "bound" indicator B10 to display digit 4 will now be described.

It will be recalled that relay BS-3 was operated to store the data for posting the "bound" range during the operations resulting from the decoding and storage of information as received from the incoming line under control of distributor DR-1. A battery connection from make contacts 625 on relay BS-3, over conductor 11 of cable 626, is extended to contact 627 of relay P4. When relay P4 is pulsing four times as brush B1 of distributor DR-2 passes segments 31, 33, 35 and 37 of ring R1, this battery connection is extended to provide four pulses through contacts 627 of relay P4, over conductor 7 of cable 619, through contacts 230 of relay GA-10, to the winding of indicator B10, to ground on relay AG, Fig. 10, over a circuit previously described, for the first impulse; and to ground through break contact 231 of indicator unit B10 for the remaining three pulses. Thus, indicator unit B10 will receive four stepping pulses and will be positioned thereby to display the digit 4. In a similar manner indicator unit C10 will be positioned under control of relays CS-1, Fig. 6, and P1 to display the digit 1. At this point, the posting of the two ranges of data as received from the remote sending point has been accomplished simultaneously. Note that the identification indicators in row 10 were not reset, since the operation of relay AGR gave a positive indication that these units were displaying the same digits as was contained in the incoming message. Relay AGR operated, at break contacts 235, removes the battery connection to the apex of pyramids 424 and 414 on the 1I and 2I storage and decoding group of relays, thereby opening all pulsing circuits to the identification range of indicators.

As brush B1 of distributor DR-2 contacts segment 43 of ring R1, a circuit is established from ground on ring R2, through brush B1 and segment 43 of ring R1, over conductor 628 to the winding of relay RL-2, to battery. Relay RL-2 operates and at its break contacts 623 opens the locking circuit for relay AG, which releases. As brush B1 of distributor DR-2 contacts segment 47 of ring R1, a circuit is established from ground on ring R2, through brush B1 and segment 47 of ring R1, over conductor 5 of cable 629, through break contacts 630 of relay PR, over conductor 631, to the winding of relay RL-3, to battery. Relay RL-3, in operating, opens the locking circuit for the BS, CS, FX, 1I, 2I and EM relays, which now release. Relay EM, Fig. 2, in releasing opens the operate path for relay AGR which then releases. Release of relay AGR opens the operate path for relay GA-10 which releases, opens the operate path for clutch magnet SM-2 of distributor DR-2 causing the brush arm to

come to rest at the end of the revolution, and closes the stepping circuit for rotary switch RS which proceeds to step over self-interrupted pulses to its homing position. As relay RL-3 operated, a circuit was closed from battery on break contacts 632 of relay WO, through make contacts 633 of relay RL-3, over conductor 5 of cable 400, over conductor 102, through make contacts 52 of relay TC, over conductor 1 of cable 53, to the winding of seeker storage indicator MP-1, to ground. Upon the release of relay RL-3, storage indicator MP-1 is advanced one position to record the posting of one complete message from line L, as previously described. The operation of relay RL-3 also opens the locking circuit for relay ST which is released as a result.

In the assumed example, there were two complete messages from line L awaiting posting while the message from line L2 was connected to the common posting equipment. The posting of the message just described has accounted for one of these messages and, at the completion of this operation, the seeker storage indicator units MR-1 and MP-1 will now be but one step out of agreement. Since they are still not in agreement, however, relay S1 will remain unoperated, and as a result, connect relay TC remains in its operated condition. Therefore, as soon as relay RL-3 releases, the start circuit for clutch magnet SM-1 of distributor DR-1 will be energized as described before and decoding and storage of the information contained in the second message from line L will proceed under control of distributor DR-1.

Blank row locator

In order to explain the action of the flight locator when the flight identification has not been previously posted on the display board, let us assume that the identification numbers 22 for fix 1, or Washington, comprise the first three characters of the second message from line L. The operations up to the point where relay EM, Fig. 2, is operated will not be described as they are similar to those outlined in detail for the first message. Operation of relay EM closes the stepping circuit for rotary switch RS as previously described. Since fix 1 is involved in this message, bank contact 1 of the FS tap switches will be marked with battery from the EM relay contacts. Referring to Fig. 7, it will be noted that the tap switches for rows 1 to 5 of the board are turned to position 1. As rotary switch RS steps to bank contacts associated with row 1, a circuit will be established to search for agreement of identification as stored on the 1I and 2I relay groups and the displayed information in row 1 as indicated on storage indicator units ITS-1 and IUS-1. Since agreement is not established on row 1, rotary switch RS continues its stepping action and next contacts bank position 2. The storage indicators ITS-2 and IUS-2 are in the blank position indicating a vacant space in row 2 of the display board. A circuit is established from contact 1 of tap switch FS-2 over conductor 2, cable 534, bank 214, contact 2 and wiper 215 of switch RS, wiper 216 and bank 217, contact 2, of switch RS, conductor 2, cable 218, wiper 549 of indicator ITS-2, contact BL of indicator ITS-2, conductor 1, cable 541, break contacts 634 of relay PR, conductor 2, cable 229, to the winding of relay VS, to ground. Thus, the action of switch RS is stopped by operation of relay VS in a manner similar to that described for relay AGR in the prior example. Relay VS initiates circuit

action identical with that described previously for relay AGR, with one exception. Relay VS does not open the battery connection to pyramids 424 and 414 of the 1I and 2I relay groups. Therefore, on actuation pulsing from distributor DR-2 and relays P1, P2, P4 and P7, the identification display board, as well as the identification storage indicators for the row selected are pulsed to the setting corresponding to the stored, decoded information on pyramids 424 and 414 of relay groups 1I and 2I. This is necessary since the flight number had not been previously posted.

Automatic wipe-out

In order to explain the automatic wipe-out feature, assume a message received from the aircraft over the Baltimore fix contains a report of flight 22 over Baltimore at 33 minutes after the hour. The transmission of characters over line L2 would then be 222133L, wherein the first two characters represent the identity, the third the fix, the fourth the range (over, or V), the fifth and sixth the time data, and the last the end-of-message signal. Operations up to and including the pulsing of the display board indicators for this message are similar to those described previously and will therefore not be repeated. Assume then, that these operations have advanced to the stage where distributor DR-2 is in operation and brush B1 is about to contact segment 44 of ring R1.

As brush B1 of distributor DR-2 contacts segment 44 of ring R1, a circuit is established from ground on ring R2, through brush B1 and segment 44 of ring R1, over conductor 6 of cable 629, through make contacts 635 of operated relay VTS-1, over conductor 636 to the winding of wipe-out relay WO, to battery. Note that any of the VTS relays operated closes the path for operation of relay WO, so that whenever an over range is posted, relay WO will be operated subsequently. In the example noted, relay VTS-1 will have been operated in order to post the digit 3 in the tens digit of "over" range. Relay WO operated, locks over its make contacts 637 and conductor 7 of cable 629 to break contacts 638 of relay AG, to ground.

Relay WO operated, closes paths to operate and hold all of the restoration relays, viz., VR, BR and CR. The circuit for operating VR may be traced from battery on make contacts 639 of operated relay WO, over conductor 1 of cable 640, to the winding of relay VR, to ground. Circuits to relays BR and CR are similar.

As brush B1 of distributor DR-2 contacts segment 45 of ring R1, a circuit is established from ground on ring R2, through brush B1 and segment 45 of ring R1, over conductor 9 of cable 619, through make contacts 236 of operated relay GA-6 (which is embodied in the equipment of row 6, Fig. 2), to the winding of solenoid SO-6, to ground. Solenoid SO-6 and the storage indicator units in row 6 are identical with units indicated for row 1, and like equipment reference numbers apply in both cases. The solenoids SO are designed so that when energized, they rotate cam shafts 237, which in turn bring four contact springs 238, 239, 240 and 241 on the storage indicator units into electrical contact with the contacts 242, 243, 244 and 245 on the storage indicator units, in accordance with the angular setting of the display drums, thereby applying ground 246 to certain of the contact springs, and in turn to certain of the conductors 1 to 247 of cable 247. For a more detailed description

of the above operation, reference may be had to said Patent 2,302,769. It will be apparent that operation of solenoid SO—6 results in the connection of a plurality of outgoing conductors to ground in accordance with the permutation code on the contacts of the indicators in the selected row, such permutations being in direct relation to the characters displayed on the drums of the indicator units.

In the present instance, an "over" report has been posted on row 6 for flight 22 at Baltimore. The posting of an "over" range causes the automatic wipe-out of this flight posting at the previous fix along the airway. However, in order to determine the location of the previous fix, it is first necessary to ascertain the inbound direction of the flight at Baltimore. This is obtained by decoding the coded information stored on the "bound" range digit of the display in row 6 of the Baltimore fix section. Assuming the flight is progressing in a southward direction, indicator B6 will be displaying the digit 4, and as solenoid SO—6 operates, conductors 18 and 20 of cable 247 will be grounded in accordance with the permutation code on the storage contacts of indicator B6. Tracing these grounded conductors in cable 247, it will be found that conductor 18 terminates at the winding of relay BT—2, Fig. 3, and conductor 20 at the winding of relay BT—4. The other terminal of the BT relay windings is connected to battery and therefore relays BT—2 and BT—4 are operated. The right hand, or locking, windings of relays BT—2 and BT—4 are not energized at this time. As relays BT—2 and BT—4 operate, a circuit is established from ground on outer break contacts 300 of relay BT—1, through make contacts 301 of relay BT—2, through break contacts 302 of relay BT—3, through make contacts 303 of relay BT—4, over conductor 2 of cable 305 to the winding of direction relay S, Fig. 5, to battery. Relay S operates and locks through its make contacts 542 and conductor 6 of cable 541, to make contacts 641 of relay WO, to ground.

As brush B1 of distributor DR—2 contacts segment 46 of ring R1, a circuit is established from ground on ring R2, over brush B1 and segment 46 of ring R1, through conductor 2 of cable 629, through make contacts 543 of Baltimore fix relay FX—2, over conductor 544 to the left hand winding of auxiliary fix relay FX2—A, to battery. Relay FX2—A operates and locks over right hand winding and make contacts 545 by way of conductor 6, cable 541, to make contacts 641 of relay WO, to ground. As brush B1 of distributor DR—2 contacts segment 47, a circuit is established to operate release relay RL—3 as described in detail hereinbefore, and the FX—2, EM, AGR, GA—6, VT and VU relays are caused to release thereby. While the original locking circuit for the 1I and 2I storage relay groups is opened by the operation of relay RL—3, these relays do not release since the locking circuit has been supplemented by an additional locking path from relay WO operated. This circuit may be traced from battery at make contact 642 of relay WO, over conductor 6 of cable 400 to the locking contacts of the 1I and 2I relay groups. Thus, while fix, range and data storage relays for the "over" posting at Baltimore have been released, the identity storage relays have been held operated. In addition, a reference to the "over" posting is retained by the operated WO relay, a reference to the Baltimore fix is retained by the operated FX2—A relay, and a reference to the bound direction is retained by the operated S relay. Note that the operation

of RL—3 relay at this time does not energize the stepping circuit to the seeker storage indicator MP—2 since the circuit is opened at break contacts 632 of relay WO. Thus the seeker is prevented from connecting another message to the common posting equipment at this time.

As brush B1 of distributor DR—2 contacts segment 49 of ring R1, a circuit is established from ground on ring R2, through brush B1 and segment 49 of ring R1, over conductor 1 of cable 629, through make contacts 546 of S relay, through make contacts 547 of operated relay FX2—A, to the winding of the FX—3, or Philadelphia, fix relay, to battery. Relay FX—3 operates and locks over its normal locking circuit which has been reestablished by the release of relay RL—3 as brush B1 left segment 47 of ring R1 on distributor DR—2. The operation of relay FX—3 establishes the proper fix section for the wipe-out operation on a southbound flight reporting over Baltimore.

As brush B1 of distributor DR—2 contacts segment 50 of ring R1, a circuit is established from ground on ring R2, through brush B1 and segment 50 of ring R1, over conductor 3 of cable 629, through break contacts 643 of relay PR, through make contacts 644 of operated relay WO, over conductor 2 of cable 541 to conductor 3 of cable 509 to the winding of relay EM, Fig. 2, to battery. Relay EM operates and locks over a circuit previously described. Relay EM operated, starts the operation of the flight locator circuit in the usual manner and the gang relay GA—9 for the ninth row containing identification number 22 (Fig. 7) in the Philadelphia fix section is operated. Operation of relay AGR in the flight locator circuit again closes the circuit of clutch magnet SM—2, and distributor DR—2 is reoperated. As brush B1 passes the even numbered segments 2 to 20, and relay P7 receives ten pulses, the indicators in row 9 of the Philadelphia fix section of the display board, as well as the storage indicators ITS—9 and ITU—9, are restored to the blank position. It will be recalled that relays VR, BR and CR are held operated over circuits from make contacts on operated relay WO. The restoration pulsing circuits for the V, B and C range indicators are therefore under control of these relays in a manner previously described. Make contacts 645 and 646 of operated relay WO supply restoration battery to pulse the identity display board indicators and the storage indicators ITS—9 and IUS—9 to the blank position.

As relay AG, Fig. 6, operates when brush B1 reaches segment 22 of ring R1, the locking circuit for relay WO is opened and relay WO releases. The release of relay WO opens the locking circuits for relays FX2—A and S, which now release. At this point, the circuits conditioned by the automatic wipe-out operation are normal and the remainder of the operations initiated by distributor DR—2 are as previously described for an ordinary posting operation, it being understood that no actuation pulses to the indicators in row 9 are transmitted, since no data storage relays are operated at this time.

By use of similar circuits, an "over" report of a northbound flight posted on the fix 3, or Philadelphia, section of the flight progress board would initiate a wholly automatic wipe-out operation of the flight posting at the previous fix 2, or Baltimore, section of the display board. In this instance, a circuit is established by the operation of the N, or north, direction relay, and auxiliary fix 75 relay FX3—A, to select the flight at the FX—2

section of the board for wipe-out operation. For purposes of simplicity, only the circuits involved in a northbound or southbound flight, reporting "over" at fix 3 or fix 2, respectively have been included in the drawings, since the automatic wipe-out circuits involving other directions of flight and other fixes are similar to those illustrated.

Automatic retransmission to other boards

Referring to Fig. 7, assume that flight 43, posted in row 1 of the Washington fix section on the flight progress board, is about to enter the area controlled by the airport tower operator. At this time it is desirable that the auxiliary board located at the airport tower duplicate the information for this flight which is at present posted only on the main airways traffic control display board. The automatic retransmission of all existing information relative to flight 43 as displayed on the main flight progress board is initiated as the Washington controller transmits a message which causes the digit 8 to be displayed in the "control" data range. This may be accomplished by a suitable transmitter, such as the teleprinter 3 of Fig. 1, which is located at the control center. In this instance, the digit 8 in the "control" range is an arbitrary figure meaning "cleared to the Washington tower." The auxiliary posting board, and its associated equipment responsive to incoming signals for selecting and actuating the proper groups of display indicators, may be in accordance with either the aforesaid Marshall et al. Patent 2,246,449 or the posting board and associated equipment of the instant disclosure, although only one "fix" posting group of indicators is required and a smaller number of ranges of data are posted.

As the data for C range is stored on the CS relays, Fig. 6, relays CS-1 and CS-4 will be operated, storing the pulsing code for digit 8. A circuit is thereby established from battery on make contacts 647 of relay CS-4, through break contacts 648 of relay CS-3, break contacts 649 of relay CS-2 and make contacts 650 of relay CS-1, over conductor 5 of cable 541, through make contacts 548 of operated fix relay FX-1 (Washington), over conductor 3 of cable 541 to the winding of relay PA to ground. Relay PA operates and locks over its make contacts 651 and conductor 652 to break contacts 653 and battery on relay RL-4. Relay PA operated, through make contacts 654, 655 and 656, grounds conductors 14, 10 and 7 in cable 229 which terminate at the windings of relays VM, EM and CM, respectively, Fig. 3. As the solenoid SO-1, Fig. 2, operates from segment 45 of distributor DR-2 in a manner previously described, the storage translating relay groups ITT, IUT, YTT, VUT, BT and CT of Figs. 2 and 3 will have certain of their relays operated in accordance with the settings on the drums of the display storage indicators in row 1 of the flight progress board. Operated relays in groups ITT and IUT are locked over their right hand windings and conductors 12 and 13 of cable 229 to break contacts 658 and 659 and battery 660 on relay RL-3, Fig. 6. Operated relays in groups VTT, VUT, BT and CT are locked over their right hand windings, through conductors 1, 2, 3 and 4 of cable 306 and windings of relays VM, EM and CM, to grounded conductors 14, 10 and 7 of cable 229. Therefore, any storage translating relays, operated as a result of solenoid SO-1 operation, will remain locked under control of relays PA and RL-3. It will be recalled

that the message under consideration has caused the posting of digit 8 in the C range. Therefore, relays CT-2 and CT-3 will have been operated as solenoid SO-1 operated. A circuit is thereby established from battery through break contacts 307 of relay CT-1, make contacts 308 of relay CT-2, make contacts 309 of relay CT-3, break contacts 310 of relay CT-4, conductor 3 of cable 305, make contacts 549 of relay FX-1, conductor 4 of cable 541 to the winding of relay PR, to ground. Relay PR operates and locks over the same locking circuit as that described for relay PA.

Relay PR operated opens the operate circuit for release relay RL-3, so that relay RL-3 is prevented from operating as brush B1 of distributor DR-2 contacts segment 47 of ring R1. Since relay RL-3 is not operated, the fix relay FX-1 and the storage translating relay groups ITT and IUT are not released at this time. The seeker connection for the message is also retained since the stepping of seeker storage indicator MP is dependent on RL-3 relay operation. Relay PR operated, opens the clutch magnet SM-2 circuit at break contacts 641 of relay PR so that the brush arm of distributor DR-2 will come to rest at the end of the revolution in progress.

Operation of distributor DR-3

As brush B1 of distributor DR-2 contacts segment 48 of ring R1, a circuit is established from ground on ring R2 through brush B1 and segment 48 of ring R1, over conductor 4 of cable 629, through make contacts 661 of relay PR, and conductor 5 of cable 229, to the winding of start magnet SM-3 of distributor DR-3, Fig. 3, to battery. Distributor DR-3 is thereby set into operation. It will be recalled that the posting in question has been made on a row of the flight progress board which is displaying the flight identification numbers 43. Therefore, as solenoid SO-1 operated, relays ITT-2 and ITT-4 of the identification tens translating group of relays, and relays IUT-1 and IUT-3 of the identification units translating group of relays, were operated in accordance with the storage indicator code on the contacts of the drums of the tens and units storage indicators, row 1, of the display board. The pyramidal contacts of the translating groups of relays operating from the storage indicators are designed to translate from the storage indicator code to the teleprinter code. Thus, pyramid 249 of the ITT relay group will, in the present example, ground conductors 2 and 4 of cable 250. The circuit may be traced from ground on make contacts 251 of relay ITT-2 to conductor 2, and ground on make contacts 252 of relay ITT-4 through break contacts 253 of relay ITT-3 and make contacts 254 of relay ITT-2 to conductor 4. Over similar circuits, the other translating relay groups ground various conductors in cable 250 in accordance with the five unit teleprinter code for the stored units identification number and data digits.

As brush B1 of distributor DR-3 contacts segment 2 of ring R1, a circuit is established from ground on ring R2, through brush B1 and segment 2 of ring R1, over conductor 255 to the winding of relay RPS-1, to battery. Relay RPS-1 operates, and at its armature and make contacts 256 extends the circuit from grounded conductors 2 and 4 of cable 250 to conductors 2 and 4 of cable 311 and thence to selector magnets 2 and 4 of reperforator RPF. The circuit to operate selector magnet 2 of reperforator RPF may be traced from

grounded conductor 2 of cable 250 to make contacts 312 of relay RPS-1, over conductor 313 to conductor 2 of cable 311, to winding of selector magnet 2 of reperforator RPF, to battery. The circuit over conductor 4 of cable 250 is similar.

As brush B1 of distributor DR-3 contacts segment 3 of ring R1, a circuit is established to operate relay RPP over a path from ground on ring R2 of distributor DR-3, through brush B1 and segment 3 of ring R1, over conductor 3 of cable 229, to the winding of relay RPP, to battery. Relay RPP operated closes a circuit from ground on its make contacts 315, over conductor 316, to the winding of punch magnet PM of reperforator RPF, to battery. As the punch magnet of reperforator RPF is energized, the code elements 2 and 4 for the character 4 are perforated in the tape 317. Upon completion of the punching stroke, the selector magnets 2 and 4 of reperforator RPF are mechanically reset to their unoperated condition. As brush B1 of distributor DR-3 contacts segments 5 and 6 of ring R1, the second identification character is punched in tape 317 under control of relays RPS-2 and RPP.

The third character, representing the fix digit is perforated next under control of relays RPS-3 and RPP which operate as brush B1 contacts segments 8 and 9 of ring R1. The code elements for this character are selected from circuits originating at contacts of the operated fix relay, in this case relay FX-1, Fig. 5. It will be recalled that the transmitted character for fix 1 was the teletypewriter character 1 and therefore fix relay FX-1 conditions the operation, at this time, of selector magnets 1, 2, 3 and 5 of reperforator RPF. The circuits may be traced from make contacts 550, 551, 552 and 553 on relay FX-1, over conductors 1, 2, 3 and 4 of cable 554, to make contacts 318, 319, 320 and 321 of relay RPS-3, over conductors 1, 2, 3 and 5 of cable 311 to selector magnets 1, 2, 3 and 5 of reperforator RPF, to battery.

It will be noted on Fig. 7 that row 1 of the display board does not show data posting for the "over," or V, range. As explained before, if no V translating relays are operated, relay VM, Fig. 3, remains unoperated. With relay VM unoperated, segment 2 of ring R2 on distributor DR-3 remains ungrounded and therefore, as brush B1 passes over segments 11 to 18 of ring R1, no action results. Row 1 of the display board does contain data for B and C ranges, however, and therefore relays BM and CM will be operated. Relay BM operated grounds segment 3 of ring R2 on distributor DR-3 over a circuit from ground on make contacts 322 of relay BM, over conductor 2 of cable 323 to segment 3, ring R2. A similar circuit from operated relay CM grounds segment 4 of ring R2.

As brush B1 of distributor DR-3 contacts segment 20 of ring R1, a circuit is established to operate relay RPS-7 over a path similar to that previously described for operation of relay RPS-1. Relay RPS-7 operated, by means of make contacts 324, 325 and 326, grounds conductors 1, 2, and 5 of cable 311. Thus, the code elements 1, 2 and 5, representing the B range digit 2, are selected for the next character perforation in the tape. As brush B1 contacts segments 23 to 30, the B data, C range and C data characters are perforated in tape 317. Relay RPS-11, operating from segment 32 of ring R1, is arranged to select the L, or end-of-message, character as the final perforation in tape 317.

As brush B1 of distributor DR-3 contacts segment 34 of ring R1, a circuit is established from

ground on ring R2, through brush B1 and segment 34 of ring R1, over conductor 6 of cable 229, through make contacts 630 of relay PR, over conductor 631 to the winding of relay RL-3, to battery. Relay RL-3 now operates with results as described previously.

As brush B1 of distributor DR-3 contacts segment 25 of ring R1, a circuit is established over conductor 11 of cable 229 to make contacts 644 of relay WO, so that, if the message just received had contained an "over" report and relay WO were operated thereby, the automatic wipe-out operation would be initiated at this time. With the example under consideration, relay WO is not operated and therefore no action results from this circuit at this time.

As brush B1 of distributor DR-3 contacts segment 38 of ring R1, a circuit is established over conductor 9 of cable 229 to operate relay RL-4. Relay RL-4 operated opens, at its break contacts 653, the locking circuit for relays PA and PR. Relays PA and PR thereupon release and in turn cause the release of the data translating relay groups BT and CT, as well as relays BM and CM. At this point all circuits have been returned to normal in readiness for reception of the next message.

From the foregoing description, it will be evident that a coded message has been perforated in tape 317 which comprises the exact context necessary to cause the tower display board to duplicate the current information displayed on row 1 of the main flight progress board. The coded intelligence characters in tape 317 are transmitted by means of tape transmitter 327 and transmitter distributor 328 to line 329 which in turn terminates at the receiving distributor of the auxiliary, or tower, display board diagrammatically indicated in the figure.

40 Automatic retransmission of revised information

Assume that an additional message is received which causes a posting in the "over," or V, range of flight 43 on the Washington fix section of the main flight progress board. Since this flight has already been cleared to the tower as evidenced by the display of the digit 8 in the control range, it is apparent that the new information posted on the main board should also be retransmitted to the tower display board. Note that in this case, the retransmission should not be a duplication of all the information displayed on row 1 of the main board, but rather should be a retransmission only of the new or revised information posted by the latest message. A description of the circuit operations to accomplish this retransmission will now be given.

Since the posting operation under consideration does not contain data 8 for C range, the circuit to operate relay PA will not be established. However, as solenoid SO-1 is operated following the posting of the "over" range on row 1 of the Washington fix section, translating relays CT-2 and CT-3 will be operated under control of indicator C-1, which has been positioned to display the digit 8 by the previous posting operation, causing relay PR to operate as explained previously. Relay PR operated performs the same functions as described for the previous example. However, in the present case, since relay PA is unoperated, the ground connection from make contacts of relay PA to the windings of relays VM, BM and CM has not been established. A ground connection to the winding of relay VM has been established over conductor 1

of cable 657 by make contacts 662 of relays VUS connected in parallel to ground. (Certain of the VUS relays will be operated to store the data pulsing code for the units digit of V range.) The VTT and VUT groups of translating relays will therefore lock over their locking windings through relay VM, to ground. The BT and CT groups of translating relays will fail to lock since their locking winding circuits are open at the EM and CM relay coil terminals. The operation of distributor DR-3 will therefore cause tape 317 to be perforated to contain the identification, fix, V range, V data, and end-of-message characters only, segments 3 and 4 of ring R2 on distributor DR-3 being ungrounded due to relays BM and CM remaining unoperated.

Automatic alarm circuits

The system provides an indicator such as lamp 444, Fig. 4, which operates whenever relay groups 1I and 2I are set to positions representative of code signals other than the code signals for the digits 1 to 9 and 0 such as may result from the failure of line L, static conditions, faulty operation of the teleprinter keyboard, and the like. Lamp 555 of Fig. 5 provides a similar indication for the data relay decoding groups.

Another warning indication is provided by lamp 663, Fig. 6, which is operated whenever the VS and WO relays are operated simultaneously. The circuit may be traced from battery on make contacts 256 of relay VS, over conductor 3 of cable 229, through make contacts 664 of relay WO, over conductor 665 to the winding of relay AR, to ground. Relay AR operates and locks over its make contacts to battery on break contacts 666, of release key ARK. Relay AR operated closes a circuit from battery on its make contacts 667, to lamp 663, to ground, causing lamp 663 to light. The operation of lamp 663 is a warning to the operating personnel that an "over" report has been received from an unscheduled aircraft reporting over a fix, relay WO operated denoting reception of an "over" report and relay VS operated denoting the flight number has not been previously posted. The "over" report of an unscheduled aircraft would require immediate action on the part of the operating personnel in order to fit the particular flight into the general traffic flow. Lamp 663 provides the alarm feature to initiate such procedure. Following proper control action, operation of key ARK opens the locking circuit to relay AR which is thereby released, extinguishing lamp 663.

Manual wipe-out

Provision has been made for wipe-out of all information in any item row of the display board by means of local teleprinter operation. Such an operation would be necessary in the event a flight plan already displayed on the progress board were cancelled, or to wipe-out the display at the final fix section of a control center where the automatic wipe-out feature would not apply.

To initiate such a wipe-out operation, the local operator at teleprinter 3 would transmit a message containing the identification number and fix section number of the flight in question in the same manner as hereinbefore described. However, in place of the range character 1, 2, or 5, the wipe-out character 7 would next be transmitted, followed by the standard end-of-message character. As this message is connected by the seeker in the common posting equipment, operations under control of distributor DR-1 are iden-

tical to those previously described up to the point where the character 7 is stored on the range decoding relays R-1 to R-5 of Fig. 5. Operation of relays R-1, R-2 and R-3, corresponding to code 7, completes a circuit through pyramidal contacts on relays R-1 to R-5 to operate relay WO. The circuit may be traced from ground on make springs 540 relay R-1, Fig. 5, through make springs 541 relay R-2, the make combination of springs 542 of relay R-3, break springs 553 of relay R-4, break springs 558 of relay R-5, over conductor 1 of cable 541 to the winding of relay WO, Fig. 6, to battery and ground. Relay WO operated conditions the pulsing circuits so that all indicators in the selected row will be restored to their blank position as explained in the automatic wipe-out description.

Relay WO operated also closes a path from battery on make contacts 668 over conductor 15 of cable 229, over conductor 1 of cable 416, to the winding of relay ST, Fig. 4, to ground. Relay ST is thereby operated and opens at its break contacts 418, the ground circuit to segments 4 and 5 of ring R42 of distributor DR-1. Therefore, as brush E6 passes segments 4 and 5 of ring R42, no stepping circuit is completed to the tape transmitter. On the next revolution of distributor DR-1, the end-of-message character is stored and decoded as hereinbefore described and the flight locator and pulsing distributor DR-2 action follows. The indicators in the selected row of the display board are thus restored to blank under control of operated relay WO.

Various modifications of the circuit arrangements and apparatus shown, and the various equivalents or substitutes for the devices illustrated, will readily occur to those versed in the art without departing from the spirit and scope of the present invention. The disclosure, therefore, is for the purpose of illustrating the principles of the invention which is not to be regarded as limited except as indicated by the scope of the appended claims.

What is claimed is:

1. In an airway schedule posting system, a flight progress board divided into panels one for each fix and each panel comprising a plurality of rows of changeable indicators for displaying flight data including overtimes, means for posting the overtime of a flight at a fix in the corresponding fix panel in the particular space displaying data for that flight as previously posted, and means acting automatically upon the posting of an overtime for a flight at a particular fix panel to cause the data for that flight at the preceding fix panel to be wiped-out by the restoration to blank positions of the indicators displaying such data.
2. A system for posting information regarding a plurality of items, comprising an announcing board having a plurality of electro-responsive posting devices assignable at different times to different ones of said items, and arranged in different display groups respectively classified in regard to different particulars of an item, each posting device including a plurality of display means respectively actuatable to different settings for displaying a plurality of data concerning one of said items, a source of message posting signals comprising item and display group designation and data in regard to an item, means responsive to said item and display group designation signals for selecting a particular display group and a posting device within said group assigned to the item represented by the item designation signals,

means controlled by said item data signals for posting the data represented thereby on the selected posting device, and means responsive to the reception of certain display group and datum signals in an incoming message for effecting, at another of the display groups, automatic wipe-out of the posted data there in regard to the item.

3. A system for posting information regarding the movements of aircraft, comprising an announcing board having a plurality of electro-responsive posting devices assignable at different times to different flights respectively of said aircraft, and arranged in groups respectively classified in regard to different fixes traversed by the aircraft, each posting device including a plurality of means respectively actuatable to different settings for posting a plurality of data concerning one of said aircraft, a source of message posting signals comprising flight and fix designation and flight data in regard to an aircraft, means responsive to said flight and fix designation signals for selecting a particular fix group and a posting device within said group assigned to the flight represented by the designation signals, means controlled by said flight data signals for posting the data represented thereby on the selected posting device, and means responsive to the reception of certain fix and datum signals in an incoming message for effecting, at another of the fix posting groups, automatic wipe-out of the posted flight data there in regard to the aircraft.

4. A system for posting information regarding the movements of aircraft, comprising an announcing board having a plurality of electro-responsive posting devices assignable at different times to different flights respectively of said aircraft, and arranged in groups respectively classified in regard to different fixes traversed by the aircraft, each posting device including a plurality of means respectively actuatable to different settings for posting a plurality of data concerning one of said aircraft including a datum representing the course of the aircraft, a source of message posting signals comprising flight and fix designation and flight data in regard to the aircraft, means responsive to said flight and fix designation signals for selecting a particular fix group and a posting device within said group assigned to the flight represented by the designation signals, means controlled by said flight data signals for posting the data represented thereby on the selected posting device, and means controlled in accordance with said posted datum representing the course of the aircraft and responsive to the reception of certain fix and datum signals in an incoming message for effecting, at a fix posting group which is prior in order of travel of the aircraft, automatic wipe-out of the posted flight data there in regard to the aircraft.

5. A system for posting information regarding the movements of aircraft, comprising a display board having a plurality of groups of electro-responsive indicators, each group being assignable at different times to different flights respectively of said aircraft, and arranged in sections respectively classified in regard to different fixes traversed by the aircraft, said indicators actuatable to different settings for posting data concerning one of said aircraft including a time datum and a datum representing the course of said aircraft, a source of message posting signals comprising flight and fix designation and flight data including a time datum in regard to the aircraft, means responsive to said flight and fix designation signals for selecting a particular fix

section and a group of indicators within said section assigned to the flight represented by the designation signals, means controlled by said flight data signals for posting the data represented thereby on the selected posting device, and means controlled in accordance with said posted datum representing the course of the aircraft and responsive to the reception of the current fix designation of the aircraft and a time datum in an incoming message for effecting, at a fix section next in the rear of said current designated fix, automatic wipe-out of the posted flight data there in regard to the aircraft.

6. A system for posting information regarding the movements of aircraft, comprising a display board having a plurality of groups of electro-responsive indicators, each group being assignable at different times to different flights respectively of said aircraft, and arranged in sections respectively classified in regard to different fixes traversed by the aircraft, said indicators actuatable to different settings for posting data concerning one of said aircraft including a time datum and a datum representing the course of said aircraft, a source of message posting signals comprising flight and fix designation and flight data including a time datum in regard to the aircraft, means responsive to said flight and fix designation signals for selecting a particular fix section and a group of indicators within said section assigned to the flight represented by the designation signals, means controlled by said flight data signals for posting the data represented thereby on the selected posting device, and means controlled in accordance with said posted datum representing the course of the aircraft and responsive to the reception of the current fix designation of the aircraft and a time datum in an incoming message for effecting, at a fix section prior in order of time, automatic wipe-out of the posted flight data there in regard to the aircraft.

7. A system for posting information regarding a plurality of items, comprising an announcing board having a plurality of groups of electro-responsive indicators assignable at different times to different ones of said items, each group having at least one indicator actuatable to different settings for posting the designation of an item and having other indicators respectively actuatable to different settings for posting a plurality of different kinds of data in regard to the item, means for selectively setting any of said item designation posting indicators to designate a given item, means for receiving an incoming message comprising posting signals including an item designation accompanied by different kinds of data to be posted relating to the item and in which the number and kind of the data may vary in different messages, means responsive to the item designation signals for automatically finding and seizing a particular group of indicators having an item designation setting corresponding to the item designation signals, other groups of signal storage devices respectively for storing said different kinds of data in the message, means controlled by the stored data signals for actuating the proper ones of said other indicators of the seized group for posting the received data notwithstanding that the number and kind of said data may vary in different messages, and means for obviating the necessity of repeating said item designation in the message when it contains a plurality of said different kinds of data, comprising means for preventing release of the seized group of indicators.

cators until all of said different kinds of data in the incoming message have been posted.

8. A system for posting information regarding a plurality of items, comprising an announcing board having a plurality of groups of electro-responsive indicators assignable at different times to different ones of said items, each group having at least one indicator actuatable to different settings for posting the designation of an item and having other indicators respectively actuatable to different settings for posing a plurality of different kinds of data in regard to the item, means for selectively setting any of said item designation posting indicators to designate a given item, means for receiving an incoming message comprising posting signals transmitted in succession and including an item designation accompanied by different kinds of data to be posted relating to the item and in which the number and kind of the data may vary in different messages, means responsive to said item designation signals for automatically finding and seizing a particular group of indicators having an item designation setting corresponding to the item designation signals, other groups of signal storage devices respectively for storing said different kinds of data in the message, means for successively applying the incoming data signals to said other signal storage devices, means controlled by the stored data signals for actuating concurrently the proper ones of said other indicators of the seized group for posting said different kinds of data notwithstanding that the number and kind of said data may vary in different messages, and means for obviating the necessity of repeating said item designation in the message when it contains a plurality of said different kinds of data, comprising means for preventing release of the seized group of indicators until all of said different kinds of data in the incoming message have been posted.

9. A system for posting information regarding the movements of aircraft, comprising an announcing board having a plurality of groups of electro-responsive indicators assignable at different times to different flights respectively of said aircraft, each group having at least one indicator actuatable to different settings for displaying a flight designation and other indicators respectively actuatable to different settings for displaying a plurality of different kinds of data in regard to the flight, means for selectively setting any of said flight designation display indicators to designate a given flight, a source of message posting signals transmitted in succession and comprising a flight designation accompanied by different kinds of data to be posted relating to the flight and in which the number and kind of data may vary in different messages, means including a group of storage devices responsive to said flight designation signals for automatically finding and seizing a particular group of indicators having a flight designation setting corresponding to the flight designation signals, other groups of signal storage devices respectively for storing said different kinds of data in the message, means for successively applying the incoming data signals to said other signal storage devices, means controlled by the stored data signals for actuating simultaneously the proper ones of said other indicators of the seized group for displaying said different kinds of data notwithstanding that the number and kind of said data may vary in different messages, and means for obviating the necessity of repeating said item designation in the message when it contains a plurality of said dif-

ferent kinds of data, comprising means for preventing release of the seized group of indicators until all of said different kinds of data in the incoming message have been posted.

5. 10. A system for posting information regarding a plurality of items, comprising an announcing board having a plurality of groups of electro-responsive indicators, assignable at different times to different ones of said items, and selectively actuatable to different settings for posting a plurality of data in regard to the item, an automatic transmitter for transmitting permutation code signals comprising a message embodying an item designation and a plurality of different kinds of data relating to the item, means including a group of storage devices responsive to item designation signals for automatically selecting a particular group of indicators, other groups of signal storage devices respectively for storing said different data embodied in the message, a receiving distributor operative in a plurality of successive cycles during the reception of each message from said transmitter, said distributor having a plurality of groups of contact elements repeatedly operated during said successive cycles, at least one of said groups of contact elements applying item designation signals to the item designation storage devices during the first cycle of the distributor and others of said groups of contact elements applying data signals to the data storage devices during said successive cycles of the distributor, re- 20 vertive control means operative to cause the transmitter to transmit said signals successively as said groups of contact elements are operated during the first cycle of the distributor and to prevent the transmission of signals when said item designation contacts are operated during the remaining cycles of the distributor for the reception of the message, and means controlled by said stored data signals for actuating said other indicators of the selected group for posting the received data.

15 30 35 40 45 50 55 60 65 70 75 11. A system for posting information regarding a plurality of items, comprising an announcing board having a plurality of groups of electro-responsive indicators assignable at different times to different ones of said items, each group having at least one indicator actuatable to different settings for posting the designation of an item and having other indicators respectively actuatable to different settings for posting a plurality of different kinds of data in regard to the item, means for selectively setting any of said item designation posting indicators to designate a given item, an automatic transmitter for transmitting permutation code signals comprising a message embodying an item designation and a plurality of different kinds of data relating to the item, means including a group of storage devices responsive to item designation signals for automatically finding and seizing a particular group of indicators having an item designation setting corresponding to the item designation signals, other groups of signal storage devices respectively for storing said different data embodied in the message, a receiving distributor operative in a plurality of successive cycles during the reception of each message from said transmitter, said distributor having a plurality of groups of contact elements repeatedly operated during said successive cycles, at least one of said groups of contact elements applying item designation signals to the item designation storage devices during the first cycle of the distributor and others of said groups of contact elements applying data signals to the data storage

devices during said successive cycles of the distributor, revertive control means operative to cause the transmitter to transmit said signals successively as said groups of contact elements are operated during the first cycle of the distributor and to prevent the transmission of signals when said item designation contacts are operated during the remaining cycles of the distributor for the reception of the message, and means controlled by the stored data signals for actuating said other indicators of the selected group for posting the received data.

12. A system for posting information regarding a plurality of items, comprising an announcing board having a plurality of groups of electro-responsive indicators, assignable at different times to different ones of said items, and selectively actuatable to different settings for posting a plurality of different kinds of data in regard to the item, a tape transmitter for transmitting permutation code signals comprising a message embodying an item designation and a plurality of different kinds of data relating to the item, means including a group of storage devices responsive to item designation signals for automatically selecting a particular group of indicators, other groups of signal storage devices respectively for storing said different data embodied in the message, a receiving distributor operative in a plurality of successive cycles during the reception of each message from said transmitter, said distributor having a plurality of groups of contact elements repeatedly operated during successive cycles, at least one of said groups of contact elements applying item designation signals to the item designation storage devices during the first cycle of the distributor and others of said groups of contact elements applying data signals to the data storage devices during said successive cycles of the distributor, revertive control means operative to step the transmitter to cause it to transmit said signals successively as said groups of contact elements are operated during the first cycle of the distributor and to prevent stepping of the transmitter when said item designation contacts are operated during the remaining cycles of the distributor for the reception of the message, and means controlled by said stored data signals for actuating said other indicators of the selected group for posting the received data.

13. In a system of the character described, a main flight display board having settable indicators for posting information in regard to a plurality of aircraft, a source of incoming posting signals for setting the indicators of the main board in regard to said aircraft, an auxiliary display board having settable indicators for displaying flight information, signal transmitting means for effecting retransmission of selected ones of the items of information currently posted on the main board to the auxiliary display board thereby to duplicate said information in regard to certain of said aircraft, and means automatically operative subsequent to the aforesaid retransmission to the auxiliary board for causing changes in the information posted on the main board in regard to said certain of the aircraft to be relayed automatically by said signal retransmitting means to said auxiliary board to reset the corresponding indicators thereof.

14. In a system of the character described, a main flight display board having settable indicators for posting information in regard to a plurality of aircraft, a source of incoming posting signals for setting the indicators of the main

board in regard to said aircraft, an auxiliary display board having settable indicators for displaying flight information, signal transmitting means for effecting retransmission of selected ones of the items of information currently posted on the main board to the auxiliary display board thereby to duplicate said information in regard to certain of said aircraft, and means automatically operative subsequent to the aforesaid retransmission to the auxiliary board for causing changes in the information posted on the main board in regard to said certain of the aircraft to be relayed automatically by said signal retransmitting means to said auxiliary board to reset the corresponding indicators thereof, said signal retransmitting means comprising signal storage means controlled in accordance with the display positions of the settable indicators for storing the signals to be retransmitted and a transmitter controlled by the stored signals for retransmitting the information to the auxiliary board.

15. In a system of the character described, a main flight display board having a plurality of groups of settable indicators respectively for posting information in regard to a plurality of aircraft, each of said groups including an indicator settable to different positions for posting different control data relevant to the associated aircraft, a source of incoming posting signals for setting the indicators of the main board in regard to said aircraft, an auxiliary display board having settable indicators for displaying flight information, signal transmitting means automatically operative when each of said indicators for posting said control data is actuated to a predetermined setting for effecting retransmission of selected ones of the currently posted items of information to the auxiliary display board to duplicate said information in regard to certain of said aircraft, and means automatically operative subsequent to the aforesaid retransmission to the auxiliary board for causing changes in the information posted on the main board in regard to said certain of the aircraft to be relayed by said signal retransmitting means to the auxiliary board to reset the corresponding indicators thereof.

16. A system for posting information regarding the movements of aircraft, comprising an announcing board having a plurality of groups of electro-responsive indicators assignable at different times to different flights respectively of said aircraft, each group having at least one indicator actuatable to different settings for displaying a flight designation and other indicators respectively actuatable to different settings for displaying a plurality of different kinds of data in regard to the flight, means for selectively setting any of said flight designation display indicators to designate a given flight, a source of message posting signals transmitted in succession and comprising a flight designation accompanied by different kinds of data to be posted relating to the flight and in which the number and kind of the data may vary in different messages, means including a group of storage devices responsive to said flight designation signals for automatically finding and seizing a particular group of indicators having a flight designation setting corresponding to the flight designation signals and operative when no group has such flight designation for finding and seizing an available idle group of indicators, other groups of signal storage devices for storing said different kinds of data in the message, means for successively applying the incoming data signals to said other signal storage devices, means for ob-

viating the necessity of repeating said item designation in the message when it contains a plurality of said different kinds of data, comprising means for preventing release of the seized group of indicators until all of said different kinds of data in the incoming message have been posted, and means controlled by the stored signals for actuating simultaneously the proper ones of the indicators of the seized group for displaying said different kinds of data notwithstanding that the number and kind of said data may vary in different messages and also the flight designation when an idle group of indicators has been seized.

17. A system for posting information regarding a plurality of items, comprising an announcing board having a plurality of groups of electro-responsive indicators assignable at different times to different ones of said items, and selectively actuatable to different settings for posting a plurality of data in regard to the item, means comprising a tape transmitter for transmitting permutation code signals comprising a message embodying an item designation, data selection and a plurality of different kinds of data relating to the item, means responsive to the item designation signals for selecting a particular group of indicators, a plurality of groups of data signal storage devices, data-selection storage devices for selecting said data signal storage groups, a receiving distributor having groups of contact elements for applying incoming data selection signals to the data-selection storage devices during reception of a message by the distributor, and revertive control means conditioned by said data-selection storage devices for causing said distributor to step the transmitter a variable number of times during reception of the data signals depending upon the number of characters embodied in the data signals.

18. A system for posting information regarding the movements of aircraft, comprising an announcing board having a plurality of groups of electro-responsive indicators assignable at different times to different flights respectively of said aircraft, each group having at least one indicator actuatable to different settings for displaying a flight designation and other indicators respectively actuatable to different settings for displaying a plurality of different kinds of data in regard to the flight, means for selectively setting any of said flight designation display indicators to designate a given flight, a source of message posting signals transmitted in succession and comprising a flight designation and data to be posted relating to the flight, means including a group of storage devices responsive to said flight designation signals for automatically finding and seizing a particular group of indicators having a flight designation setting corresponding to the flight designation signals and operative when no group has such flight designation for finding and seizing an

available idle group of indicators, other groups of signal storage devices for storing said data in the message, means for applying the incoming data signals to said other signal storage devices, an alarm means, means controlled by the stored signals for actuating the indicators of the seized group for displaying said data and also the flight designation when an idle group of indicators has been seized and means automatically effective for operating said alarm means to attract attention to such occurrence.

19. A system for posting information regarding the movements of aircraft, comprising an announcing board having a plurality of groups of electro-responsive indicators assignable at different times to different flights respectively of said aircraft, each group having at least one indicator actuatable to different settings for displaying a flight designation and other indicators respectively actuatable to different settings for displaying a plurality of different kinds of data in regard to the flight, means for selectively setting any of said flight designation display indicators to designate a given flight, a source of message posting signals transmitted in succession and comprising a flight designation and "over" report data to be posted relating to the flight, means including a group of storage devices responsive to said flight designation signals for automatically finding and seizing a particular group of indicators having a flight designation setting corresponding to the flight designation signals and operative when no group has such flight designation for finding and seizing an available idle group of indicators, other groups of signal storage devices for storing said data in the message, means for applying the incoming data signals to said other signal storage devices, an alarm means, means controlled by the stored signals for actuating the indicators of the seized group for displaying said "over" report data and also the flight designation when an idle group of indicators has been seized and means automatically effective for operating said alarm means to attract attention to the fact that an "over" report has been received in regard to a flight which is not currently posted on the announcing board.
